UNITED STATES PATENT OFFICE.

SAMUEL A. BROMBERG, OF RICHMOND, VIRGINIA.

HOOK AND EYE.

SPECIFICATION forming part of Letters Patent No. 738,655, dated September 8, 1903.

Application filed January 13, 1903. Serial No. 138,845. (No model.)

To all whom it may concern:

Be it known that I, SAMUEL A. BROMBERG, a citizen of the United States, residing at Richmond, in the county of Henrico and State of Virginia, have invented a new and useful Improvement in Hooks and Eyes, of which the following is a specification.

This invention relates to new and useful improvements in hook-and-eye fasteners for garments; and its object is to provide a fastener of this character which is of novel construction and is provided with retaining means within the eye whereby the hook may be securely held in position therein unless more than ordinary backward and downward pressure is exerted thereupon.

The invention consists in providing an eye formed of a single piece of wire and having an intermediate or engaging portion, from the ends of which project rearwardly-extending arms, which are so shaped as to form eyes and are then bent inward between the arms and laterally to form Y-shaped retaining-jaws. The hook is also formed of a single piece of wire, so shaped as to comprise a shank, having eyes at one end and a rearwardly-extending diamond-shaped head at the opposite end, said head being substantially equal in width to the distance between the arms of the eye at the forward ends thereof.

The invention also consists in the further novel construction and combination of parts hereinafter more fully described and claimed, and illustrated in the accompanying drawings, showing the preferred form of my invention, and in which—

Figure 1 is a plan view showing my improved hook and eye in engagement with each other. Fig. 2 is a side elevation thereof, and Fig. 3 is a perspective view of the hook.

Referring to the figures by numerals of reference, 1 is a preferably curved intermediate or engaging portion of the eye, the same being provided at each end with a rearward continuation or arm 2, said arms being preferably tapered toward each other. An eye 3 is formed at the rear end of each arm and a forwardly-extending retaining spring-strip 4 projects from each eye and between the arms 2, said strips being preferably tapered toward each other and provided at their free ends

with extensions 5, which project laterally therefrom and form substantially Y-shaped jaws, which are located at the rear of the center of the engaging portion 1 of the eye. The hook employed in connection with the eye above described is also preferably formed of a single piece of wire, the same being so bent at the center as to form a diamond-shaped head 6, preferably of a width equal to the distance between the forward ends of the arms 2, and this head extends over and is parallel with the forward end of the shank 7 of the hook, said shank being integral therewith and having eyes 8, formed at the opposite end thereof by bending the ends of the wire constituting said hook against the sides of the shank.

To use the fastener herein described, the hook and eye are secured to a garment in the ordinary manner and the diamond-shaped head 6 is then inserted under the eye and brought into contact with the inner surfaces of the Y-shaped jaws 5. The head 6 is preferably very short and merely of sufficient length to permit the same to extend over the engaging portion 1 of the eye, and it is obvious, therefore, that when the two parts are placed in engagement with each other it is necessary to overlap the same but slightly. After the hook has been brought into contact with the jaws it is pressed thereagainst until brought past the plane of the engaging section 1. The two heads of the fastener are then drawn in opposite directions and the hook will, as is obvious, engage the portion 1 of the eye. As soon as this engagement takes place the jaws 5 spring back into normal positions in rear of the engaging portion 1, and it is therefore impossible to disengage the hook from the eye unless the same is moved backward with sufficient pressure to force the jaws 5 apart to enable the diamond-shaped head 6 to pass therebetween. Each jaw 5 will, as is obvious, bear upon one side of the head 6, and the two therefore serve as retainers of the head, no matter in what position the same may be moved in relation to the engaging portion 1.

In the foregoing description I have shown the preferred form of my invention; but I do not limit myself thereto, as I am aware that modifications may be made therein without

departing from the spirit or sacrificing the advantages thereof, and I therefore reserve the right to make such changes and alterations as may fall within the scope of my invention.

5 Having thus described my invention, what I claim as new, and desire to secure by Letters Patent, is—

In a garment-fastener of the character described, the combination with a shank having eyes at one end, a hook at the other end and a diamond-shaped head upon the hook; of an eye formed in a single strip and adapted to be engaged by the hook, said eye comprising an intermediate or engaging portion, 15 arms extending from the ends thereof and inclined toward each other, eyes at the free

ends of said arms for the reception of securing means, retaining-strips extending from said eyes to the points between the arms, said strips being tapered toward each other, and 20 outwardly-projecting free ends to the retaining-strips having lateral movement, said ends being adapted to form jaws for contacting with the sides of the head of the hook and holding the same in position within the eye. 25

In testimony whereof I affix my signature in presence of two witnesses.

SAMUEL A. BROMBERG.
